CLAIM

The ornamental design for a watch, as shown and described.

DESCRIPTION

FIG. 1 is a perspective view of a watch, showing the new design;

FIG. 2 is a front view thereof;

FIG. 3 is a rear view thereof;

FIG. 4 is a left-side view thereof;

FIG. 5 is a right-side view thereof;

FIG. 6 is a top view thereof; and,

FIG. 7 is a bottom view thereof.

The words "CIGA Design" forming part of the claimed design is a registered trademark of SHENZHEN CIGA Design Co., Ltd., which is the applicant of the claimed design.

The broken lines show portions of the watch that form no part of the claimed design.
